CIRCULAR KNITTING MACHINE

Albert Victor Clarke, Birstall, near Leicester, England, assignor to Charnwood Engineering Company Limited, London, England

Application September 22, 1938, Serial No. 231,246
In Great Britain September 27, 1937

7 Claims. (CL 66—14)

This invention is for improvements in or relating to circular knitting machines, and is concerned with knitting machines of the type having a needle bed (e. g. a cylinder) and relatively movable cams, a second instrument bed (e. g. a cylinder) for a circular or arcuate series of instruments (e. g. needles) adapted to co-operate with the needles of the first bed, relatively movable cams for said instruments, and means for driving said beds, or the two sets of cams as the case may be, which means includes a drive member rotatable or oscillatable (or both rotatable and oscillatable) about an axis offset from the axis of the second bed and connected to said bed or to its associated cams, in which machine the second bed and its cams are displaceable about the drive member out of and into register with the first bed. In an embodiment of this type of machine which is the subject of my co-pending patent application No. 175,943, filed Nov. 22, 1937, of which this application is a continuation-in-part, the two beds are superimposed needle cylinders and the said cylinders are equipped with double-ended needles capable of being transferred from one cylinder to the other. The two cylinders are driven in unison by means of a vertical drive shaft which constitutes the drive member aforesaid. At its lower end this drive shaft is provided with a pinion meshing with a gear on the bottom cylinder and at its upper end is provided with a pinion meshing with a gear on the top cylinder. The top cylinder is capable of being swung about the drive shaft into and out of register with the bottom cylinder, and during movement out of register with the bottom cylinder a latch guard and a number of interchangeable feeders are brought into register with said bottom cylinder. Hence the machine may be adapted to produce rib fabric or plain fabric at will, such as example as hose or half hose having a rib top and integrally knitted therewith a plain leg, said plain leg being by the provision of the interchangeable feeders patterned with a greater facility than is usual in machines of the superimposed cylinder type. In machines of the superimposed cylinder kind means are provided for taking up wear or back lash that occurs between the pinions on the drive shaft and the gears with which they mesh on the cylinders. As will readily be appreciated one method of accomplishing this would be to adjust the cylinder closer to the drive shaft so that the gear teeth are caused to mesh more deeply. It is also desirable in a machine of the type specified (e. g. in that embodiment thereof which is the

subject to the aforesaid patent application) to provide means for taking up wear or back lash in the drive, but the method just referred to cannot readily be adopted unless special precautions are taken, for as the second bed or top cylinder is displaceable about the axis of the drive member such adjustment would result in a variation in the distance between the drive member and the said bed or top cylinder with the further result that, consequent upon such adjustment, in the case of a superimposed needle cylinder machine the tricks in the two cylinders would not be aligned with that accuracy that is essential and analogous irregularities would also result in other machines of the aforesaid type. A specific object of this invention is to overcome this difficulty. Therefore the invention provides a knitting machine of the type specified, characterised in that the second bed and the cams are displaceable about a pivot which is independent of the drive member and the latter is adjustable within small limits towards and away from the bed.

In order that the invention may be better understood it will be described in detail, as applied to a machine according to the aforesaid co-pending patent application, with reference to the accompanying drawings, in which

Figure 1 is an elevation of the machine with the top cylinder displaced;

Figure 2 is a plan thereof;

Figure 3 is a vertical section through the cylinders, showing the driving mechanism;

Figure 4 is a section on the line 4—4 in Fig. 3, looking in the direction of the arrows, while

Figure 5 is a section illustrating an alternative means of adjustment.

The two cylinders 10, 11 are connected by means of a vertical drive shaft 16 having at its bottom end a pinion 15' meshing with a gear 14' on the bottom cylinder 11, and at its top end a pinion 15 meshing with a gear 14 on the upper cylinder 10. This drive shaft 16 is partially enclosed in a vertical standard 140 provided at its top end with a spigot-like bearing member 140', which is received in a bore in a bracket or plate 13 that also supports the top cylinder 10 and its cam box 12. This bracket or plate 13 is movable on a ring 17 about the said bearing member 140' to swing the top cylinder 10 into and out of register with the bottom cylinder 11.

In the movement to the inoperative position shown in Fig. 1 the feed plate 20 is carried with the top cylinder 10, and advantageously, simul-

taneously with this movement, a latch guard ring 45, on which a battery of interchangeable yarn feeders 43 is mounted, is swung about pivot 18 into register with the bottom cylinder 11. These 5 feeders are operated from pin drum 50 which is racked from control drum 89.

The present invention is applicable to a machine in which the said top cylinder 10 and its 10 cam box 12 are displaceable by hand, but it is illustrated as applied to a machine in which said parts are displaceable under power applied by the drive shaft 16 and pinion 15. Briefly, displacement is effected by placing a restraint upon relative movement between cylinder 10 and cam 15 box 12. To do so rocker 36 is operated by means of push rod 37 from control drum 189 to permit wedge 34 to rise and key 31 to move under the influence of spring 32 into slot 33 of member 26. The said member 26 is rotatably mounted on a 20 sleeve 24 at the top of the cylinder 10 and has projections 28 received between compression springs 29, 30 in slots 27 in a member 27 fast on the sleeve 24. Hence the cylinder is prevented from rotating and swings (according to the direction of rotation or oscillation of drive shaft 16) over ring 17 until brought to rest by one or other of resilient stops 38, 39. Any shock caused by the engagement of key 31 in slot 33 is taken up by the compression springs 29, 30, and when the cylinder reaches its appointed position and is brought to rest by one of the said resilient stops any delay in withdrawing the key merely serves to compress springs 29, 30, further.

Means, such as plunger 40 operated through 35 the lever 41 from a suitable control (e. g. a control drum) are provided for locking the upper cylinder 10 in each of its extreme positions.

The vertical drive shaft 16 is supported by 40 means of a bearing which is secured in the upper end of the vertical standard 140, but this bearing is adjustable within said standard to cause the drive shaft 16 to approach slightly towards or to recede from the cylinder axis. By this adjustment the gear teeth by which the top cylinder 10 45 is driven may be correctly meshed without variation in the distance between the axis of the top cylinder and the axis about which it swings, and without throwing the tricks of the two cylinders out of alignment. It may here be noted that although consequent upon such adjustment the axis of the drive shaft 16 and the axis of displacement of the cylinder 10 may not coincide exactly, the discrepancy is small, and the cylinder 50 is still displaceable about the drive shaft.

This bearing may consist of a bush 142 received within the interior of the pivot 140' aforesaid and having a bore in which the vertical drive shaft 16 rotates. The said bush 142 has a clearance in 60 the interior of the pivot 140' and is provided with a flange 142' that is drilled at one point with a hole through which a pivot screw 144 extends up into the material of the standard, see Figs. 3 and 4. Substantially diametrically opposite this pivot 65 hole the flange 142' is pierced with an arcuate or tangential slot 143, through which a clamping screw 144' extends into the material of the standard 140. Hence after the two said screws 144, 144' have been slackened, the bush 142 may be 70 adjusted within the standard 140, and about the pivot screw 144, so as to cause its shaft-receiving bore to approach towards or to recede from the cylinder 10. An adjustment screw 145 or screws 75 may be provided for securing a fine adjustment.

Instead of there being a single slot 143 opposite

a pivot screw 144, there may be two diametrically opposed slots such as 143 (the second slot being shown in dotted lines in Fig. 4).

In an alternative arrangement illustrated in Fig. 5 the bush 242 has its shaft-receiving bore 5 eccentric to its outer periphery, so that by rotating the eccentric bush the axis of the drive shaft 16 is displaced relatively to the axis about which the cylinder 10 swings. Means such as a set screw or the like 243 may be provided for clamping 10 said bush in the desired position of adjustment.

In a like manner an adjustable bush 142a (which may follow either of the alternatives just described) may be provided for adjusting the 15 lower pinion 15', which meshes with a gear 14' on the bottom cylinder 11, said bottom bush 142a being adjustable either in a bore at the base of the standard 140 or in a bore formed in a suitable 20 part of the machine frame.

I claim:

1. In a circular knitting machine of the opposed needle cylinder kind, having two opposed needle cylinders, a set of cams for each cylinder, a drive shaft and gears for effecting simultaneous 25 relative rotation of the cylinders and cams, wherein one cylinder and its cams is displaceable, substantially about the axis of the drive shaft, laterally out of and into register with the other cylinder, said drive shaft having its axis substantially parallel with that of said other cylinder; a bearing for the drive shaft, means for adjusting it to take up back lash in the gearing for effecting relative rotation between the displaceable cylinder and its cams, and a pivot, for pivotal displacement of the displaceable cylinder and its cams, which pivot occupies a fixed location substantially coaxial with the drive shaft.

2. In a circular knitting machine comprising a pair of beds for knitting instrumentalities, and 40 driving means therefor disposed eccentrically thereof, one of said beds being movable to and from a position in axial alignment with the other bed, the combination of a pivot for said movable bed surrounding but independent of said driving 45 means; and means for adjusting said driving means within but independently of said pivot towards and away from said movable bed.

3. In a circular knitting machine comprising a pair of beds for knitting instrumentalities, and 50 driving means therefor, one of said beds being movable to and from a position in axial alignment with the other bed, the combination of a pivot for said movable bed having a fixed location eccentric to the axis of said beds; a bearing for 55 said driving means inside and approximately concentric with said pivot; and means for adjusting the bearing inside the pivot to cause said driving means to approach toward and recede from the movable bed.

4. In a circular knitting machine comprising a pair of beds for knitting instruments, operating means for the instruments of each bed, and driving means for effecting relative movements of at least partial rotation between each bed and its 65 associated operating means to cause movement of the instruments, in which machine one of the beds and its driving means is movable to and from an operative position in which it is in register with the other bed without severing the 70 driving connection afforded by said driving means for effecting the said relative movements between the movable bed and its associated operating means, and the said driving means includes a drive member offset from the movable 75

bed and arranged to make movements of at least partial rotation about an axis in transmitting the drive; the combination of a pivot for said movable bed substantially coaxial with the drive member but independent thereof, and means for adjusting the drive member, independently of the pivot, towards and away from the movable bed.

5. In a circular knitting machine comprising a pair of opposed instrument cylinders, a cam box 10 for each of them, which cylinders and boxes are arranged to make relative movements of at least partial rotation, and driving connections including a drive shaft for imparting said relative movements to one cylinder and its box, which 15 drive shaft has its axis parallel to that of said one cylinder but is located outside said cylinder, in which machine said one cylinder and its box are displaceable, about an axis which is substantially coincident with that of the drive shaft, into 20 and out of register with the other cylinder without disconnection of said driving connections; the combination of a pivot for the displaceable cylinder and its box, which pivot is substantially coaxial with the drive shaft but is independent 25 thereof, a bearing for the drive shaft, and means for adjusting said bearing to cause the drive shaft to approach towards and recede from the displaceable cylinder and in said movement to change the relation of its axis to the axis about 30 which the cylinder is displaceable.

6. In a circular knitting machine comprising a pair of beds for knitting instrumentalities, means associated with each bed for actuating the instrumentalities therein by relative movements of at 35 least partial rotation between each bed and its associated actuating means, and driving means

for effecting said relative movements, in which machine one of the beds is displaceable into and out of axial register with the other bed about an axis and the driving means includes a driving member that is arranged to make movements of 5 at least partial rotation about an axis, which is at least substantially coincident with said axis of displacement, in effecting the aforesaid relative movements between the displaceable bed and its associated actuating means; the combination of 10 means for maintaining the axis of the displaceable bed at a constant radius from the axis of displacement, and means for adjusting the axial position of said driving member in relation to both said axis of displacement and the axis of the 15 displaceable bed and for thereby taking up back lash in the drive.

7. In a circular knitting machine comprising a pair of beds for knitting instrumentalities, actuating means associated with each bed for actuating the instrumentalities thereof, and driving means disposed eccentrically of said beds for producing movements of at least partial rotation between each bed and its associated actuating means, one of said beds being movable to and 20 from a position in axial alignment with the other bed, the combination of a pivot for the movable bed having a fixed location eccentric to the axes of said beds, a bearing for the driving means, which pivot and bearing are substantially concentric, and means for adjusting the bearing in 25 relation to the pivot to cause said driving means to approach toward and recede from the movable bed.

ALBERT VICTOR CLARKE. 35
